SHELF UNIT

Hans P. Jorgensen, 1931 Raby Road,
Haslett, Mich. 48840

Filed Apr. 14, 1970, Ser. No. 22,501

Term of patent 14 years

Int. Cl. D6—99

U.S. Cl. D33—3

FIG. 1

FIG. 2

FIG. 3

FIG. 6

FIG. 4

FIG. 7

FIG. 5

FIG. 1 is a perspective view of a shelf unit showing my new design;

FIG. 2 is a front elevational view of the unit illustrated in FIG. 1;

FIG. 3 is a top plan view of the unit illustrated in FIG. 1;

FIG. 4 is a back elevational view of the structure illustrated in FIG. 1;

FIG. 5 is a bottom plan view of the unit illustrated in FIG. 1;

FIG. 6 is an elevational view of one end of the structure illustrated in FIG. 1; and

FIG. 7 is an elevational view of the other end of the unit illustrated in FIG. 1.

I claim:

The ornamental design for a shelf unit, as shown.
